HIGH-FREQUENCY ELECTRICAL
COMMUNICATION SYSTEM

Prafulla Kumar Chatterjea and Leslie Wilfred Houghton, London W. C. 2, England, assignors to Standard Telephones and Cables Limited, London, England, a British company

Application December 10, 1942, Serial No. 468,572
In Great Britain December 16, 1941

13 Claims. (Cl. 250—17)

1

In nearly all time modulated pulse systems used for transmitting intelligence of any kind, the amplitude of the signal obtained at the receiver is some function of the total time occurring between the leading and trailing edges of a pulse in a train of time modulated pulses and it is necessary to determine in general the duration of each individual pulse to reconstruct the intelligence.

A method of and arrangements for utilising pulses which are time modulated as a function of the amplitude of a sound or like wave have been proposed in which the desired intelligence can be obtained from one edge only of the said time modulated pulse.

The operation of this latter system is dependent upon transmitting a train of pulses so time modulated that said pulses have a function characteristic of the amplitude of a sound or like wave (hereinafter also called "intelligence wave"), said time modulation being characterised in that the time interval between the limits of modulation is equal to the time taken for a fraction (preferably less than $\frac{1}{2}$) of a wavelength period of a radio frequency (this frequency itself is large compared with the pulse repetition frequency). At a receiver said pulses are used to interrupt a train of oscillations (these being at the carrier, i. e. at the said radio frequency) and the amplitude of the intelligence wave received is a function of the amplitude of the damped oscillations at the interruptions of the pulse train, which in turn is dependent at any moment on the time duration of the pulses—this duration being modulated by the intelligence wave in the manner described hereinbefore.

The main requirement of such a system is to have at the transmitter a constant carrier (or radio) frequency generator which is set into oscillation by one edge of a sharp short pulse (say the loading edge). This oscillation builds up to a steady value in a time depending on the sharpness of the initial rise of the pulse, among other factors, and the duration of the pulse. The trailing edge of the same pulse in this case initiates another forced oscillation into the circuit, the initial amplitude of this second set of oscillations being determined mainly by the duration of the pulse, other factors being constant.

Ideally of course the edges of the pulse have to be absolutely straight to make possible the proper control of the initial stage of the damped oscillation, this is in general rather difficult to achieve without extra precaution in the circuit design.

2

A signal of this character is audible with quite good quality in a broadcast receiver designed for the reception of amplitude modulated waves.

Another method and arrangements have been proposed for achieving more or less the same ends by modifying the slope of one of the edges of the pulses—preferably the edge which normally occurs at equal intervals of time, and preferably the trailing edge. Here then the slopes of the trailing edge are characteristic of the amplitudes of a sound or like wave. In practice, it is found that actually both edges are modified.

The special advantages obtained from these methods and arrangements are various, and particular

usefulness lies in the dissemination of propaganda, stoppage of unwanted transmission, or transmission of intelligence over a large band of frequencies. For example, one signal can transmit intelligence within ± 6 db. level over a band width of 300 kc./s., the signals being received at frequency intervals throughout this band and the intervals being solely governed by the frequency of repetition of the pulses.

The present invention has for its object to provide another method of and other arrangements for achieving similar results. Another object of the invention is to render frequency modulation intelligible in an amplitude modulation receiver. An electrical signal transmission system accord-

ing to the invention is characterised in that once a pulse train has been initiated, i. e. a pulse duration of a certain repetition frequency has been decided upon, the frequency or phase of the carrier alone is varied either directly or indirectly according to the instantaneous amplitude of the intelligence wave.

If f_c be the carrier frequency at which the transmitter output is tuned, a change of this f_c equal to $\pm \Delta f_c$ is made characteristic of the amplitude of the intelligence wave, whilst the pulse duration, the pulse repetition frequency, and the pulse slope are maintained constant.

According to a feature of the invention the trains of oscillations have initial amplitudes which are characteristic of the modulating intelligence wave. As in all pulse transmission systems the transmission assumes the characteristics of a number of satellite side band transmissions.

Using only the frequency modulation system according to the present invention, intelligible reception cannot now be obtained in receivers designed only for amplitude modulated waves because a detector for amplitude modulated waves by itself is immune to variations of frequency of

the applied wave. It will be convenient at this point to indicate something of the relation between phase modulation and frequency modulation.

It will be appreciated that frequency modulation and phase modulation are so related that taking the simplest conception, a frequency modulated wave is one with unvarying amplitude whose frequency is varied cyclically above and below a mean unmodulated value, and phase modulation in its simplest form can be shown to result in frequency modulation.

In Fig. 1 of the accompanying drawing is shown a vector OP representing an unmodulated carrier frequency $\omega/2\pi$ where $\omega=2\pi f$, f being the frequency. Let its phase be advanced and retarded sinusoidally (say) between $+\varphi_1$ and $-\varphi_2$ with respect to the unmodulated state ($\varphi_0=0$), the vector remaining constant during the operation. This results in a peak-to-peak modulation

$$(\varphi_1 + \varphi_2)$$

but it is important to note that only at the extreme excursion positions is the frequency of the wave identical to the unmodulated state, the frequency having alternately increased and decreased with frequency maxima and minima occurring at P, the unmodulated state. In other words, the instants of maximum phase displacement and maximum frequency change are displaced from each other by 90° at the modulating frequency. Thus if phase modulation is assumed to be a certain function Ψ , the frequency modulation is inherently the rate of change of phase, i. e., the frequency modulation is a function, $\dot{\Psi}$ where $\dot{\Psi}$ is the first differential with respect to time of Ψ . A very simple case is shown here to express the similarity between frequency modulation and phase modulation. It is known that constant phase modulation at all modulating frequencies results actually in more frequency modulation when higher modulation frequencies are used than for lower modulating frequencies.

In one way of carrying out the invention constant duration pulses are used, since the deviation of the carrier frequency is made characteristic of the intelligence. This is achieved by frequency-modulating a carrier wave in a certain predetermined manner, and then modulating by a train of pulses of constant duration. The application of phase modulation to provide a similar result will be apparent to those skilled in the art from the description hereinbefore given on the similarity between phase and frequency modulation. The term "angular modulation" is used herein to denote both frequency and phase modulation.

The invention will be further elucidated in the following description. Referring to Fig. 2 of the accompanying drawing, a pulse which is applied to a resonant circuit is shown as of such duration that one cycle of a carrier wave applied to the same circuit is allowed to occur. The pulse is shown as occurring as the oscillation swings in the positive direction and the forced oscillation set up by the trailing edge of the pulse is in opposition to the applied oscillation. Assuming that the amplitude of the forced oscillation is equal to the amplitude of the applied oscillation, the resultant amplitude of the circuit oscillation is zero, so that if the applied oscillations are interrupted at the moment of the trailing edge of the pulse, the circuit ceases to oscillate. If the oscillation frequency is as shown in Fig. 3, the voltage induced by the trailing edge 2 will be in phase with the applied oscillation, and a voltage of twice

the applied oscillation amplitude results. This is shown in chain-line in Fig. 3. This would also be the case if three or other odd number of half-cycles of the applied oscillation occurred during the pulse duration. It will be observed that the amplitude of the damped trains set up in the circuit is dependent upon the frequency of the applied oscillations, providing the applied oscillations are interrupted contemporaneously with the trailing edge of the pulse, and that the applied oscillation swings through zero during the leading edge of the pulse. There thus occurs the interaction of the damped waves due to the continued damped oscillation of the circuit on account of the applied oscillation (now terminated) and the damped oscillation set up by the change of voltage due to the trailing edge of the pulse. The result is a damped train of waves whose frequency is that of the applied oscillations and whose amplitude depends upon the relation between the pulse duration and the periodic time of the applied oscillations.

Thus if the frequency of the applied oscillations is made to depend upon the instantaneous amplitude of an intelligence or other wave, both the frequency of the damped waves and the amplitude thereof carry the intelligence and the amplitude modulation can be received by receivers designed for amplitude modulated waves, whilst frequency modulation can only be received by receivers designed for reception of frequency modulated waves. It will be understood by those versed in the art that the amplitude of the damped waves generated could be amplified and passed through a limiting device, hence eliminating the amplitude modulation. When the amplitude modulation is used, forced reception in receivers for amplitude modulated waves is obtained over a wide range of carrier frequencies and these carrier frequencies are determined by the pulse repetition frequency of the constant duration pulses applied to the circuit which produces the damped trains.

Fig. 4 shows in block diagram an arrangement for carrying out the invention. Here 3 represents a pulse generator, the output of which causes oscillator 4 to start and stop as described. The frequency at which this oscillator oscillates at any time is characteristic of the signal (i. e. the output of the modulation amplifier 5), this frequency being generated by any known method.

The details of one circuit arrangement embodying the invention is shown in Fig. 5. In this arrangement the carrier is provided by an oscillator cut in and out of use under the control of the constant duration pulses and whose frequency is under the control of the intelligence wave to be transmitted. In Fig. 5, the reference 6 indicates an oscillator valve with associated tuned circuit 7 comprising inductance L and capacity C. This oscillator is normally negatively biased so that it oscillates only during the period that a positive pulse is applied to the grid thereof from a valve 8 which is the output valve of a pulse generator. The frequency at which valve 6 oscillates is governed, not only by C, but by the input capacitance of valve 9 which is in parallel with the tuned circuit 7. By means of the circuit associated with valve 9 the input capacitance of valve 9 can be made to vary by varying its bias voltage, which can be made to represent a given modulation signal, obtained from valve 10 and its associated circuit. The valve 10 may, for instance be an amplifier for the intelligence wave to be transmitted, and whose output is passed

through a bias resistance in the grid-cathode circuit of the valve 9. A capacity 11 is connected between the grid of 9 and the tuned circuit LC of valve 6.

The resulting varying damped train formed in circuit 7 may be obtained by any known method of coupling shown in the drawing as being inductively coupled to L, and should preferably be transferred direct to a transmitting aerial indicated at A.

What is claimed is:

1. An electrical wave signal transmission system comprising means for generating short trains of damped carrier waves, an intelligence wave source, means for subjecting the carrier waves comprising said wave trains to angular modulation in accordance with the instantaneous amplitude of the intelligence wave, and means for impressing the resultant modulated wave trains upon a transmission medium.

2. An electrical wave signal transmission system comprising an oscillator for generating carrier waves, a source of constantly repetitive electrical pulses, an intelligence wave source, means for applying said pulses to said oscillator to cause it to generate short trains of carrier waves, the duration of a train after the end of the initiating pulse depending on the duration of said pulse, means for angularly modulating the carrier waves comprising said wave trains in accordance with the instantaneous amplitude of the intelligence wave, and means for impressing the resultant modulated wave trains upon a transmission medium.

3. An electrical wave signal transmission system comprising an oscillator including an electron tube having a cathode, an anode, a control grid, and regeneratively coupled anode and grid circuits, means for negatively biasing said grid to inhibit oscillation, a source of positive electrical pulses, means for applying said pulses to said grid so as to cause said oscillator to generate short trains of carrier waves, means to cause the time duration of said pulses to determine the time duration of said trains in excess of said pulses, an intelligence wave source, means for angularly modulating said trains of carrier waves in accordance with the instantaneous amplitude of the intelligence wave, and means for impressing the resultant modulated wave trains upon a transmission medium.

4. An electrical wave signal transmission system comprising means for generating short trains of carrier waves, a source of constantly repetitive electrical pulses of constant time duration, an intelligence wave source, means for angularly modulating said carrier waves comprising the respective trains in accordance with the instantaneous amplitude of said intelligence wave, a resonant circuit, means for applying said carrier waves to said resonant circuit, means for applying said pulses to said resonant circuit in such time relation with respect to said carrier waves that each pulse is applied substantially at the instant when the carrier amplitude is passing through zero amplitude in the same direction as the pulse, and means for coupling said resonant circuit with a transmission medium.

5. The method of electrical carrier wave signal transmission which comprises generating short damped trains of carrier waves, angularly modulating the carrier waves comprising the respective trains in accordance with the instantaneous amplitude of an intelligence wave to be transmitted, and amplitude modulating the initial

amplitude of the respective trains also in accordance with the instantaneous amplitude of said intelligence wave.

6. An electrical signal transmission system as claimed in claim 4 wherein the said resonant circuit is comprised in the regenerative feedback circuit of an oscillator, and the pulses are applied to set said oscillator into oscillation and are applied also to the said resonant circuit whilst the intelligence wave to be transmitted as the angular modulation of said trains of waves is applied to control the frequency of said resonant circuit.

7. An electrical signal transmission system as claimed in claim 4 wherein the said intelligence wave is applied to control a capacity in said resonant circuit.

8. An electrical signal transmission system as claimed in claim 4 wherein said resonant circuit includes a capacity comprising the grid-cathode capacity of a thermionic tube and means is provided to apply said intelligence wave to vary the grid bias of said last-mentioned tube in accordance with the amplitude of said intelligence wave.

9. An electrical signal transmission system as claimed in claim 4 wherein said resonant circuit is coupled to a radiant acting antenna.

10. The method of electrical carrier wave signal transmission which comprises generating a first series of short trains of damped carrier waves, superposing a second series of short trains of damped carrier waves on said first series, displaced a predetermined constant time with respect to said first series, and varying the frequency of said carrier waves of both said series in accordance with the instantaneous value of an intelligence wave to be transmitted.

11. An electrical wave signal transmission system comprising a resonant circuit, means to vary the resonance of said circuit in accordance with the instantaneous values of an intelligence wave to be transmitted, means to apply an oscillation at the frequency of said resonant circuit to said circuit for repeated short periods of time, whereby trains of damped oscillations are set up in said resonant circuit, means for repeatedly shocking said resonant circuit at a constant time after the setting up of said trains of oscillations, whereby additional trains of oscillations of the same frequency are set up in said circuit having a phase relation to the oscillations of said first trains which is dependent on said constant time, a transmission medium, and means for impressing the resultant modulated oscillation trains in said resonant circuit upon said transmission medium.

12. An electrical wave signal transmission system, comprising a resonant circuit, means to vary the resonance of said circuit in accordance with an intelligence wave to be transmitted, means to generate short trains of damped carrier waves in said resonant circuit at the frequency of said circuit, means to generate additional trains of carrier waves in said circuit at a constant period of time after the initiation of said first wave trains, said period of time being such as to give a maximum output of said resonant circuit as a resultant of both said trains of carrier waves for one extreme frequency adjustment of said resonant circuit, whereby the resultant of said two trains of carrier waves will depend for its amplitude on said period of time, a transmitting medium, and means for impressing said resultant modulated wave trains upon said transmission medium.

13. An electrical wave signal transmission system comprising means for generating constantly

repetitive electrical pulses of constant time duration, a resonant circuit, means to initiate in said resonant circuit trains of oscillations at the frequency of said circuit, said means being operative for the time duration of said pulses, whereby the trains of carrier waves continue as damped oscillations after the cessation of said initiating means, means to apply said pulses to said resonant circuit so as to create additional trains of

5

carrier waves by the trailing edges of said pulses, means to vary the resonance of said resonant circuit in accordance with an intelligence wave to be transmitted, a transmitting medium, and

means to impress the resultant of said trains of carrier waves in said resonant circuit upon said transmitting medium.
